Primary Examiner — Lilyana Bekic(74) *Attorney, Agent, or Firm* — Ware, Fressola, Maguire & Barber LLP(57) **CLAIM**

I claim the ornamental design for an inhaler, as shown and described.

DESCRIPTION

FIG. 1 is a front top perspective view of an inhaler according to the present invention;

FIG. 2 is a right side view of the inhaler in FIG. 1, the left side view being identical to the right side view;

FIG. 3 is a front view of the inhaler shown in FIG. 1, the back view being identical to the front view;

FIG. 4 is a top view of the inhaler shown in FIG. 1; and,

FIG. 5 is a bottom view of the inhaler shown in FIG. 1. The broken lines in the drawings depict portions of the inhaler that form no part the claimed design.
